(57) **CLAIM**

The ornamental design for a doormat, as shown and described.

DESCRIPTION

FIG. 1 is a top, front perspective view of a doormat showing my new design;

FIG. 2 is a bottom, back perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is an enlarged view of detail 9 in FIG. 1; and,

FIG. 10 is an enlarged view of detail 10 in FIG. 2.

The broken lines depict portions of the doormat and form no part of the claimed design.
